UNITED STATES PATENT OFFICE.

ROBERT H. HACKNEY, OF MILWAUKEE, WISCONSIN, ASSIGNOR TO PRESSED STEEL TANK COMPANY, OF WEST ALLIS, WISCONSIN, A CORPORATION OF WISCONSIN.

MACHINE FOR DRAWING AND SHAPING HOLLOW METAL ARTICLES.

1,011,193.

Specification of Letters Patent. Patented Dec. 12, 1911.

Application filed February 14, 1910. Serial No. 543,728.

To all whom it may concern:

Be it known that I, ROBERT H. HACKNEY, a citizen of the United States, residing at Milwaukee, in the county of Milwaukee and 5 State of Wisconsin, have invented certain new and useful Improvements in Machines for Drawing and Shaping Hollow Metal Articles, of which the following is a specification, reference being had to the accompanying drawing, forming a part thereof.

This invention relates more particularly to means for drawing and shaping tapered vessels or other hollow articles made of metal, such as bilged barrels and the like. 15 Its main objects are to facilitate and improve the manufacture of such articles.

It consists in the construction, arrangement and combination of parts as herein-after particularly described and defined in 20 the claims.

In the accompanying drawing like characters designate the same parts in the several figures.

Figure 1 is a vertical section on the line 25 1 1, Fig. 2, of a machine embodying the invention; Fig. 2 is a horizontal cross section on the line 2 2, Fig. 1, showing the die member; Fig. 3 is a horizontal section on the line 3 3, Fig. 1; Fig. 4 is a similar section on the line 4 4, Fig. 1, of the punch member; Fig. 5 is a lower end elevation or inverted plan view of the punch member; Figs. 6 and 7 are sectional views similar to Fig. 1 illustrating the operation of the 30 punch and die members and of the pressure ring; and Fig. 8 is an enlarged section on the line 8 8, Fig. 2, showing a die and associated bridge block.

For the purpose of illustration a machine 40 specially designed for drawing and shaping one-piece sheet metal barrels is shown in the drawing. The invention, however, is not limited to the production of barrels, but by such changes in the shape of the punch 45 sections and dies, and such modifications in the construction and arrangement of the parts of the machine as will be apparent to those skilled in the art to which it pertains, it may be adapted to produce from sheet 50 metal by drawing and pressing operations like or similar to those employed in the manufacture of barrels, other hollow tapering articles of various shapes for various purposes.

55 Referring to the drawing, the machine

comprises a contractile punch member *a* and an expandable die member *b*, arranged coaxially with relation to the punch member. The die member consists in the present case of a stationary ring *c*, which may be 60 mounted as shown in Fig. 1, on posts or standards *d*, and a series of radially movable dies or sections *e* surrounding the axis of the machine and guided in an internal annular recess in said ring, being held in 65 place therein by a cap ring *f*. The ring *c* is provided with a series of radially arranged hydraulic cylinders *g* and in these cylinders are fitted plungers *h*, the inner ends of which engage with or abut against 70 the dies *e*. Bridge blocks or dies *i* inserted between the several dies *e* and movably fitting into recesses in the adjoining ends thereof flush with their inner working faces, 75 span and partially close the gaps between said dies and form therewith a continuous draw line, zone or face when the dies are moved outward and separated more or less.

The dies *e* and blocks *i* as shown by Fig. 2 have their inner working faces curved or 80 shaped circumferentially of the die member to correspond as nearly as possible with the varying cross-sectional shape of the punch member *a*. As shown in Fig. 8, a portion of such working faces above and below the lower sides of the blocks *i* is made 85 straight or parallel with the axis of the machine, and forms the continuous draw line, zone or face above mentioned, which is of variable diameter. Above this draw line, 90 zone or face, both the dies *e* and blocks *i* are rounded or beveled outwardly to present a flaring opening in the die member toward the punch member, and they are 95 preferably rounded outwardly below said draw line, zone or face. By thus forming the dies *e* and blocks *i* with a portion of their working faces parallel with the axis of the machine they are relieved of excessive wear adjacent to the gaps between the dies *e* and at the ends of the blocks *i* when they are separated more or less by the expansion 100 of the die member and crimps or folds forced into said gaps in the formation of an article on the punch member, are pressed 105 down smooth as they pass the straight draw face below the gaps.

As shown in Fig. 2 the blocks *i* are provided on their outer sides with studs or 110 projections *j* which enter transverse grooves

in the dies and hold said blocks in their proper positions relative thereto when the dies are moved outwardly and separated. The cylinders *g* are supplied with liquid under the requisite head or pressure through radial passages *k* formed in the ring *e* and connected at their outer ends by branches *l* with a pipe *m* encircling said ring. The pipe *m* is in turn connected by a pipe *n* with

10 a pump or reservoir.

The punch member *a* consists in the present case of a tapering expanding core *p*, and of a number of radially movable sections *q*, connected at their ends by bolts *r* with radially slotted plates or heads *s* and *t*. The core *p* is attached at its upper end to a flanged head *u* which is in turn connected with the rod or an extension of the piston *v*. This piston is fitted in a vertical hydraulic cylinder *w* which is mounted coaxially with relation to the die *b* on a plate *x* connected by tie rods *y* with the die ring *c*, the piston rod or extension passing downwardly through a central opening and stuffing box 25 in said plate. The upper guide plate or head *s* of the punch member is formed or provided with an upwardly projecting cylindrical extension movably fitting over the flange of the head *u* and provided at its 30 upper end with an inwardly projecting stop ring or flange *z*, which by engagement with the outwardly projecting flange on the head *u* limits the downward movement of the punch sections *q* relative to the core *p*.

35 Upon the upper head or plate *s* is movably fitted a pressure ring *2*, which is formed or provided at its upper end with an outwardly projecting flange to which is attached parallel with its axis, the plungers 40 of hydraulic cylinders *4*, these cylinders being movably connected with said flange, as shown in Figs. 3 and 6, but guide rods *5*, which, passing loosely through ears or flanges on opposite sides of the cylinders, 45 are secured at their lower ends in the flange of said pressure ring and are formed or provided at their upper ends with heads or stops *6* for limiting the movement of the cylinders away from said ring when the 50 head or plate *s* and said ring are dropped into their lower positions relative to the core *p* and head *u*, as shown in Fig. 7. The head *u* is connected with the rod or extension of piston *v* by a coupling nut or collar *7*, provided with an outwardly projecting ring or flange *8* against which the upper ends of the cylinders *4* abut when they are brought into action with the plungers *3*, to press the ring *2* downwardly toward the dies *e*. The cylinders *4* are supplied with liquid under the requisite head or pressure through an annular pipe *9* connected with their upper ends and a flexible or jointed pipe *10* connecting the pipe *9* with a reservoir or pump. The 60 pressure ring *2* is formed adjacent to its up-

per end with an inwardly projecting shoulder *11*, which by engagement with an outwardly projecting shoulder *12* on the upward extension of the head or plate *s*, limits the downward movement of said ring relative to said head or plate. The cylinder *w* is supplied with liquid under the requisite head or pressure, from a pump or reservoir, through connections *13* and *14* at or near its ends.

To prevent contraction of the punch member, particularly when the dies *e* are pressing against the upper part thereof and thus tend to force the sections *q* downward on the tapering core *p*, means are provided such as for example, as an electromagnet *15*, shown in Fig. 1, to hold the head or plate *s* up against the head *u* while said punch member is being forced downward through the die member *b*. The magnet coil may be inserted in an annular recess formed in the head *u*, which will thus serve as a core and housing therefor, and arranged as shown, to act when energized upon the head or plate *s* as its armature.

In the operation of the machine, a cupped sheet metal blank is placed on the dies *e* directly below the punch member *a*, the dies *e* being thrust inward and held with yielding pressure against outward movement by the admission of liquid under the requisite head or pressure into the outer ends of the cylinders *g*. The punch being in its upper position, as shown in Fig. 1, and collapsed, as shown in Fig. 7, liquid is released from the lower end of the cylinder *w* through the connection *14* and admitted under the requisite head or pressure into the upper end of said cylinder through the connection *13*, thereby forcing the punch downward into and against the cupped blank resting on the dies *e*. When the head or plate *t* is brought into engagement with the blank the advance of the punch sections *q* is arrested and they are thrust outward into expanded position, as shown in Fig. 1, by the continued downward movement of the tapering core *p*. As the expanded punch is forced with the blank downward through the die member *b*, the metal of the blank is pressed and drawn into shape against the tapering punch by the joint action of the punch sections *q* and of the dies *e*, which gradually recede as the diameter of the punch increases. After the central and larger part of the punch has passed below the dies *e*, said dies, forced inward by the fluid pressure on the plungers *h*, gradually draw the metal of the blank inward against the punch as it diminishes in diameter. The magnet *15* being energized, holds the head or plate *s* up against the head *u* and prevents the punch sections *q* from being forced inward during the foregoing operation. As the upper and inwardly curved or tapering portion of the punch

passes by the dies *e*, and the blank is drawn inwardly and contracted, the metal of the blank above the dies is prevented from buckling and wrinkling by the pressure ring 2, which is yieldingly held down inside of the blank as shown in Fig. 6, by the admission of liquid under the requisite head or pressure into the cylinders 4, the upper ends of said cylinders being seated against the ring 10 or flange 8. After the pressure ring is brought into action its advance is arrested while the punch continues to move downward, and liquid is forced back out of the cylinders 4 as they move downward on the plungers 3. After the punch has passed completely below the dies *e* and the blank has been shaped into a barrel, current is cut off from magnet 15, thereby releasing the head or plate *s* from the head *u* and permitting the punch sections *q* to descend and move inwardly on the tapering core *p*, as shown in Fig. 7. Liquid under pressure is released from the upper end of the cylinder *w* and admitted into its lower end, thus withdrawing the piston *v* and the punch back to their upper positions. As the punch passes upwardly through the die member *b*, the dies *e* being held in their inner positions as shown in Fig. 1, force the punch sections *q* inwardly and strip the barrel therefrom, as shown in Fig. 7. The pressure ring 2 being released, when the punch sections *q* are released and moved together, descends on the head or plate *s* to its normal or initial position with the internal shoulder 11 at its upper end resting on the external shoulder 12 on said head or plate.

By the term "radial" or "radially" as herein employed to describe movements of the dies *e* and punch sections *q* it is intended to include any rectilinear or curved, simple or composite movement of said dies and punch sections toward or from the axis of the machine.

Various changes in the details of construction and arrangement of parts may be made to adapt the machine to produce articles of different shapes and for different purposes within the spirit and scope of the invention as defined by the appended claims.

I claim:

1. In a machine for drawing and shaping hollow metal articles the combination of a punch member having the form of the article to be shaped thereon, an expandable die member co-axial with the punch member and comprising a series of movable dies surrounding the axis of the machine; means for yieldingly forcing said dies inward toward said axis, and means for moving one of said members axially with relation to the other.

2. In a machine for drawing and shaping hollow metal articles the combination of a tapering punch member, an expandable die

member co-axial with the punch member comprising a series of radially movable dies surrounding the axis of the machine and having outwardly rounded or beveled working faces, means for moving one of said members axially with relation to the other, and means for yieldingly forcing said dies inward.

3. In a machine for drawing and shaping hollow metal articles the combination of a punch member of varying diameter, an expandable die member comprising a series of radially movable dies forming co-axially with the punch member a continuous draw line of variable diameter and presenting a flaring opening toward the punch member, means for moving one member axially with relation to the other, and means adapted to press said dies inward against an article on the punch and permit them to yield outwardly as one member is moved relative to the other and the diameter of the punch member varies.

4. In a machine for drawing and shaping hollow metal articles the combination of a punch member of varying diameter, an expandable die member presenting a flaring opening toward the punch member and comprising a series of radially movable recessed dies and bridge blocks movably fitting into the recesses in said dies flush with their working faces and spanning the gaps between them, said bridge blocks forming with the dies a continuous draw face of variable diameter when the dies are more or less separated, means for yieldingly pressing said dies and blocks inwardly against an article on said punch member, and means for moving one member axially with relation to the other.

5. In a machine for drawing and shaping hollow metal articles the combination of a punch member of varying diameter, an expandable die member presenting a flaring opening toward the punch member and comprising a series of radially movable recessed dies and bridge blocks movably fitting into the recesses in said dies flush with their working faces and spanning the gaps between them, the working faces of said dies and bridge blocks having a zone extending above and below the lower sides of the bridge blocks parallel with the axis of the machine and forming a circumferentially continuous draw face when the dies are more or less separated, means for yieldingly pressing said dies and blocks inwardly against an article on said punch member, and means for moving one member axially with relation to the other.

6. In a machine for drawing and shaping hollow metal articles the combination of a tapering punch member, a coaxial die member comprising a series of radially movable dies, means for pressing said dies inward

- against an article on said punch, means for moving one of said members axially with relation to the other, and an axially yielding pressure ring surrounding said punch member.
- 5 7. In a machine for drawing and shaping hollow metal articles the combination of a contractile tapering punch member comprising radially movable sections and means for moving said sections outward and holding them in working position, an expandible die member comprising a series of radially movable dies surrounding the axis of the machine, means for forcing said dies inward against an article on said punch member and permitting them to yield outward as one member is moved relative to the other, and means for moving one of said members axially with relation to the other.
- 10 8. In a machine for drawing and shaping hollow metal articles, the combination of a contractile tapering punch member comprising a series of radially movable sections and means for moving said sections outward and holding them in expanded position, a coaxial die member comprising a series of radially movable dies having working faces presented toward and substantially parallel with its axis, and outwardly rounded or beveled faces adjoining said parallel faces, means for yieldingly pressing and holding said dies against an article on the punch while one member is moved axially relative to the other, and means for moving one of said members axially with relation to the other.
- 15 9. In a machine for drawing and shaping hollow metal articles the combination of a contractile punch member of varying diameter comprising radially movable sections and means for moving said sections into and holding them in expanded position, a coaxial die member comprising a series of radially movable dies forming a continuous draw line of variable diameter, means for yieldingly pressing and holding said dies against an article on said punch while one member is moved axially relative to the other, and means for moving one member axially with relation to the other.
- 20 10. In a machine for drawing and shaping hollow metal articles the combination of a contractile tapering punch member comprising radially movable sections and means for moving said sections into and holding them in expanded position, a coaxial die member comprising a series of radially movable dies, means adapted to yieldingly press said dies inward against an article on said punch while one member is moved axially relative to the other, means for moving one of said members axially with relation to the other, and an axially yielding pressure ring surrounding said punch.
- 25 11. In a machine for drawing and shaping hollow metal articles the combination of a contractile tapering punch member comprising radially movable sections and a tapering core for expanding said sections, a coaxial die member comprising a series of radially movable dies, means for yieldingly pressing said dies inward against an article on said punch while one member is moved axially relative to the other and means for moving one of said members axially relative to the other.
- 30 12. In a machine for drawing and shaping hollow metal articles the combination of a contractile tapering punch member comprising radially movable sections and a tapering core for expanding said sections, a coaxial die member comprising a series of radially movable dies and presenting a flaring opening toward the punch member, means for yieldingly pressing and holding said dies inward against an article on said punch while one member is moved axially relative to the other, and a hydraulic cylinder and piston connected with one of said members and adapted to move the same axially relative to the other.
- 35 13. In a machine for drawing and shaping hollow metal articles the combination of a contractile tapering punch member comprising radially movable sections and a tapering core for expanding said sections, a coaxial die member comprising a series of radially movable dies and presenting a flaring opening toward the punch member, means for yieldingly pressing said dies inward against an article on said punch while one member is moved axially relative to the other, and means for moving one of said members axially relative to the other, a pressure ring mounted upon and surrounding said punch and movable axially relative thereto, and hydraulic cylinders and plungers connected with said ring and adapted to yieldingly press the same between the opposing working faces of the dies and punch inside of the article on the punch.
- 40 14. In a machine for drawing and shaping hollow metal articles the combination of a contractile tapering punch comprising radially movable sections and a tapering core for expanding said sections, a coaxial die member comprising a series of radially movable dies, means for yieldingly pressing said dies inward against an article on said punch while one member is moved axially relative to the other and means for moving one of said members axially relative to the other.
- 45 15. In a machine for drawing and shaping hollow metal articles the combination of a hydraulic cylinder and piston, a contractile tapering punch member comprising a tapering core connected with said piston and a series of sections arranged around said core and movable radially and axially relative thereto, a die member arranged coaxially with relation to the punch member and comprising a series of radially movable dies, and means for yieldingly pressing said dies inward against an article on said punch while
- 50 55 60 65 70 75 80 85 90 95 100 105 110 115 120 125 130

one member is moved axially relative to the other.

16. In a machine for drawing and shaping hollow metal articles the combination of a contractile tapering punch member comprising radially movable sections and a tapering expanding core, movable axially one relative to the other, a die member arranged coaxially with relation to the punch member and comprising a series of radially movable dies, means for yieldingly pressing said dies inwardly against an article on said punch member while one member is moved axially relative to the other, and means for moving one of said members axially relative to the other.
17. In a machine for drawing and shaping hollow metal articles the combination of a contractile tapering punch member comprising a series of radially movable sections, a tapering expanding core, and guiding heads connecting the sections at each end thereof around the core, one of said heads connecting the sections with the core and permitting axial movement of one relative to the other, a pressure ring mounted upon one of said heads and axially movable thereon over the adjacent ends of the punch sections, means for yieldingly pressing said ring toward the punch sections, means for holding the punch sections in expanded position on said core, a die member arranged coaxially with relation to the punch member and comprising a series of radially movable dies, means for yieldingly pressing said dies inward against an article on said punch member while one member is moved axially relative to the other, and means for moving one of said members axially relative to the other.
18. In a machine for drawing and shaping hollow metal articles the combination of a die ring provided with a series of radially movable dies and with radially arranged hydraulic cylinders, plungers fitting in said cylinders and adapted to press said dies inward, a plate connected by tie rods with said ring, a hydraulic cylinder mounted on said plate coaxially with relation to said ring, a piston fitted in said cylinder and projecting through said plate, a contractile tapering punch member comprising a tapering core fixed to the protruding end of said piston, a series of axially and radially movable sections fitted to said core, and guiding heads connecting said sections with one another and with the core, an axially movable pressure ring fitting over the punch member, and hydraulic cylinders and plungers interposed between said pressure ring and an opposing abutment on the piston and adapted to yieldingly press said ring toward the die member.

In witness whereof I hereto affix my signature in presence of two witnesses.

ROBERT H. HACKNEY.
